(57) **CLAIM**

The ornamental design for a hearing aid retainer, as shown and described.

DESCRIPTION

FIG. 1 is a front perspective view of the hearing aid retainer of the instant invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective environmental view illustrating the hearing aid retainer in use.

The broken lines in FIG. 1-3, 5, and 7 views are included for the purpose of illustrating portions of the hearing aid retainer that form no part of the claimed design, and the broken lines in FIG. 8 view represent the environment. None of the broken lines form a part of the claimed design.
